Inventor:

Edward A. Cooper

United States Patent Office.

EDWARD A. COOPER, OF LANCASTER, NEW YORK, ASSIGNOR TO HIMSELF
AND J. N. JOHNSON, OF SAME PLACE.

Letters Patent No. 63,478, dated April 2, 1867.

IMPROVED HARNESS SNAP.

The Schedule referred to in these Letters Patent and making part of the same.

TO ALL WHOM IT MAY CONCERN:

Be it known that I, EDWARD A. COOPER, of Lancaster, in the State of New York, (assignor to myself and J. N. JOHNSON,) have invented a new and improved Harness Snap; and I do hereby declare that the following is a full and exact description thereof, reference being had to the accompanying drawings, making a part of this specification, in which—

Figure I is a perspective view of my improved harness snap.

Figure II is a longitudinal section; and

Figure III is a section of the main body of my improved snap, showing the manner in which the spring is attached thereto.

The nature of this invention consists in the manner of securing the spring which retains the thumb-lever in position to the main part or body of the snap hook.

Letters of like name and kind refer to like parts in each of the figures.

A represents the main part or body of the snap; A¹ is the hook and A² the loop formed thereon. B represents the thumb-lever, which is hinged to the main body A by means of the rivet b'. This thumb-piece is made hollow upon its inner side, forming a groove of sufficient capacity to retain the spring C therein and to shut over and enclose the lug D.

The spring is secured to the main body of the snap in the following manner: D represents a lug, which is cast on to the main body A near its base, and projects at right angles, or nearly so, from the same, as shown in cast on to the main body A near its base, and projects at right angles, or nearly so, from the same, as shown in Fig. III. The spring is placed in its proper position upon the snap, as is also distinctly shown in Fig. III, and then by one blow of a hammer the lug D is bent over and on to the end of the spring, holding the same firmly in place. The thumb-lever B is then fitted on and hinged to the main part of the snap in a common manner.

As a modification of my invention, the lug D, instead of being cast on to the main body of the snap at an angle thereto, as shown in Fig. III, may be formed by sawing a slot into the main part A large enough to admit the end of the spring C, and then a slight blow of the hammer presses the lug so formed on to the spring and holds it firmly in place.

What I claim as my invention, and desire to secure by Letters Patent, is—

Securing the spring C to the main body of the harness snap by means of the lug D, the thumb-lever or tongue B being made so as to shut over and enclose the lug, in the manner substantially as herein described.

EDWARD A. COOPER.
